Primary Examiner — Karen S Acker(74) *Attorney, Agent, or Firm* — NSIP Law(57) **CLAIM**

We claim the ornamental design for a fabric, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a fabric showing our new design; and,

FIG. 2 is a front view of a second embodiment thereof. The dot-dash-dot broken line surrounding each figure depicts the boundaries of the claim and forms no part of the claimed design.
